Primary Examiner — Richard Edgar*Assistant Examiner* — Alexander Joseph David(74) *Attorney, Agent, or Firm* — Finnegan, Henderson, Farabow, Garrett & Dunner, LLP(57) **CLAIM**

The ornamental design for a fuel injector, as shown and described.

DESCRIPTION

FIG. 1 is a front, top, right perspective view of a fuel injector showing the new design;

FIG. 2 is a rear, bottom, left perspective view thereof;

FIG. 3 is a front elevation view thereof;

FIG. 4 is a rear elevation view thereof;

FIG. 5 is right-side elevation view thereof;

FIG. 6 is a left-side elevation view thereof;

FIG. 7 is a top plan view thereof;

FIG. 8 is a bottom plan view thereof; and,

FIG. 9 is a magnified cross-sectional top plan view thereof, as indicated at line 9-9 in FIG. 1.

The portions depicted in broken dashed lines of even length illustrate portions of the fuel injector that form no part of the claimed design.

1 Claim, 8 Drawing Sheets(56)
